UNITED STATES PATENT OFFICE

95,348

DESIGN FOR A HEATER

Herman H. Heidbreder, Quincy, Ill., assignor to
The Moore Corporation, Joliet, Ill., a corporation of Illinois

Application January 25, 1935, Serial No. 55,070

Term of patent 3½ years

To all whom it may concern:

Be it known that I, Herman H. Heidbreder, a citizen of the United States, residing at Quincy, county of Adams, and State of Illinois, have invented a new, original, and ornamental Design for Heater, of which the following is a specification, reference being had to the accompanying drawing, forming a part thereof.

In the drawing:

The figure is a perspective view showing a heater embodying my design.

The surfaces of the back and side of the stove not shown in the drawing are stippled in the same manner as the front and side illustrated in the figure, and the two sides and back surfaces carry no other ornamentation.

I claim:

The ornamental design for a heater as shown and described.

HERMAN H. HEIDBREDER.
